(57) **CLAIM**

The ornamental design for footwear, as shown and described.

DESCRIPTION

FIG. 1 is a perspective view of footwear.

FIG. 2 is a front view of the footwear of FIG. 1.

FIG. 3 is a rear view of the footwear of FIG. 1.

FIG. 4 is a right side view of the footwear of FIG. 1.

FIG. 5 is a left side view of the footwear of FIG. 1.

FIG. 6 is a top view of the footwear of FIG. 1; and,

FIG. 7 is a bottom view of the footwear of FIG. 1.

The dashed broken lines in FIGS. 1–7 show features that form no part of the claimed design. The dot-dash lines in FIGS. 1–7 define a boundary between features forming no part of the claimed design and features that form a part of the claimed design. The dot-dash lines enclose a semi-transparent overlay extending over features of the footwear forming no part of the claimed design.

1 Claim, 6 Drawing Sheets(56)
